UNITED STATES PATENT OFFICE.

JOHN J. GHEGAN, OF EAST ORANGE, NEW JERSEY.

ELECTRIC SIGNALING APPARATUS.

1,275,902.

Specification of Letters Patent. Patented Aug. 13, 1918.

Application filed December 20, 1916, Serial No. 137,934. Renewed July 3, 1918. Serial No. 243,250.

To all whom it may concern:

Be it known that I, JOHN J. GHEGAN, a citizen of the United States, and resident of East Orange, Essex county, New Jersey, 5 have made certain new and useful Improvements in Electric Signaling Apparatus, of which the following is a specification.

This invention relates to electro-magnets for use in a signaling circuit, as at a station on a telegraph line, and the object is to substitute the alternating current from a main supply circuit for the local batteries heretofore employed. These batteries, as is well known, have long been in use, and consist 15 of two or three cells, usually of zinc and copper elements, in an exciting solution; they require cleaning and renewal, and the price of zinc and copper has so far advanced that a substitute is in demand.

20 The invention applies the improvement in a relay, a sounder or recorder, or any electro-magnetic device of similar character, and preferably employs a solenoid coil and tubular core; the reciprocating and preferably pivoted bar is capable of to-and-fro movement between stops, with a retracting device, like an adjustable helical spring. This bar has independent movement and is controlled by an actuator having independent movement. The actuator moves with the tubular cores of the solenoid, and when at rest and circuit is closed, this actuator is entirely out of contact with the bar and free to vibrate under the influence of the 35 alternating current, to a degree slight and almost imperceptible, but as the actuator is practically free and clear from the bar, these vibrations of the actuator are immaterial. When current is broken or cut off 40 in any way, the actuator, under the influence of its retractor, moves upward and impacts with the bar and the bar strikes its upper fixed limit stop; when circuit is closed again, the actuator is drawn down against the influence of the spring, and the bar, assisted by a compression spring acting 45 against the force exerted by the first-named spring, strikes its lower limit stop, while the actuator, continuing its downward movement, leaves the bar and takes up an independent, separated position, where any such "chattering" resulting from current 50 alternations, is ineffective.

A sounder is referred to in the foregoing

description, but a relay or repeating sounder 55 is adapted to the same construction.

The adjustable contact carried by the bar is adapted to vary the point in the upward movement of the actuator where the actuator makes impact with the bar, or, in other words, the adjustable stop carried by the bar is used to limit and establish the extent of space through which the actuator is free to vibrate without imparting its vibrations to the bar, whereby the best position of the 60 actuator may be secured.

The accompanying drawings illustrate the invention.

Figure 1 shows a Morse telegraph sounder, to which my improvement is applied; Fig. 70 2 shows the elements of the structure in a cross-section, taken through one of the solenoid coils and including the second coil of the magnet, the retracting spring for the bar, the adjustment for said spring, the adjustable stop carried by the bar and the sliding pin passing through the bar. Fig. 3 shows a public supply alternating current circuit with step-down transformer, supplying lamps and local battery current at a 75 80 telegraph station, and a local circuit containing a sounder operated by a relay on a telegraph circuit.

In Fig. 1, the Morse sounder, *s*, has two solenoid coils, 9 and 10, fixed on a metal base, 11; the bar, *a*, has trunnion bearings at 12 and 13; there is a metal pillar, 14, fixed on base 11, and binding posts, 15, 16, for coil terminals on wooden base, 17. The support, 18, for the two bearings 12, 13, is 85 90 also supported on metal base 11. The actuator, 20, is of thin metal, and the magnet is made as free from hysteresis as possible; there are two soft iron tubular cores, *c*, which reciprocate in the solenoids to the 95 extent substantially as shown. There is a pin, *p*, firmly fixed to actuator 20; this pin *p* passes through a perforation in adjusting screw 21 and has a retracting spring, 22, supported by adjusting screw, 23; screw 23 100 is supported on bracket, 24, and bracket 24 is fixed to support, 18. The bar *a* is depressed by adjustable compression spring, 25.

When relay *r* is on its front contact and key, *k*, is closed, local circuit, 30, is 105 closed through secondary coil, 31, of the transformer, and actuator 20 is drawn down out of engagement with adjustable stop 21,

carried on bar *a*; actuator 20 vibrates or "chatters" slightly, and almost imperceptibly, but to an immaterial extent, and spring 25 holds bar *a* on its down contact, 5 32; contact stop 32 engages post 14, while pin *p*, sliding through stop 21, permits the described movement. When relay *r* is on its back contact, local circuit 30 is open, spring 22 retracts actuator 20, and, with an impact, 10 actuator 20 strikes screw stop 21 on bar *a*, and bar *a* strikes its upper limit or back stop 33. It results that when dots and dashes of the Morse alphabet are transmitted by key *k*, the bar *a* strikes stops 32 and 33, alternately in exact conformity with key movements, and the sound resulting sharply defines dots and dashes as transmitted.

What I claim is:—

- 20 1. In an electromagnetic signaling device the combination of an electromagnet, a pivoted, rigid contact bar, a retractor therefor, a rigid, resonant back stop for said bar, an actuator for said bar, means whereby said actuator under closed circuit conditions, moves with said bar and a fixed contact stop in position to arrest said bar and permit said actuator to disengage itself.
- 25 2. In a Morse code signal receiving device the combination of an electromagnet, a reciprocating member, an actuator therefor controlled by said magnet and located between said member and magnet, a spring retractor for said member; a spring retractor for said actuator, means whereby when circuit is closed, said member and said actuator move in engagement, and a fixed contact stop, in position to arrest said member at an intermediate point in said movement.
- 30 3. The combination of an electromagnet, a pivoted, reciprocating bar, fixed, rigid, front and back stops therefor, an actuator reciprocating intermediate said bar and magnet, a retractor common to both bar and actuator, an alternating current circuit for said magnet, a circuit breaker in said circuit and means whereby said actuator and bar move in engagement in one direction and move in engagement and then separate at an intermediate point, on the opposite movement.
- 35 4. The combination of an electromagnet, a pivoted, reciprocating bar, fixed front and back stops therefor, an actuator reciprocating intermediate said bar and magnet, a retractor common to both bar and actuator, an alternating current circuit for said magnet, a circuit breaker in said circuit and means whereby said actuator and bar move in engagement under open circuit condi-

tions, and move in engagement and separate when the bar reaches a fixed contact stop, under closed circuit conditions.

5. The combination with an alternating current circuit and means for making and breaking said circuit, of an electromagnet, a pivoted, reciprocating, resonant bar, a reciprocating actuator for said bar, and means whereby actuator and bar move together under open circuit conditions and move together and separate when said bar engages a fixed contact stop, under closed circuit conditions. 65

6. In a code telegraph receiving magnet the combination with an alternating current circuit and a circuit breaker therefor of an electromagnet in said circuit, a reciprocating member; fixed, up and down contacts therefor; an actuator to control said member in response to both open and closed circuit conditions, and means whereby actuator and bar move in engagement on open circuit and move together and then separate on closed circuit. 75

7. In a code telegraph receiving magnet the combination with an alternating current circuit and a circuit breaker therefor of an electromagnet in said circuit, a reciprocating bar, a reciprocating actuator, two opposite stops therefor, and means whereby said bar and actuator move together to engage one stop when circuit is open, and move together but separate when said bar engages its opposite stop and circuit is closed. 85

8. The combination in an electromagnetic signal device of an alternating current circuit, and a circuit breaker therefor of an electromagnet, a pivoted reciprocating, rigid bar, a separate actuator therefor, a retractor common to both, a retractor adapted to oppose said retractor in controlling said bar, an up contact stop for said bar and actuator, a down contact stop for said bar, and means whereby said actuator is attracted to said magnet, moves with said bar, and leaves said bar when it engages the fixed down contact. 95

9. In a receiving magnet for a code telegraph the combination with an alternating current circuit and a circuit breaker therefor of an electromagnet in said circuit, a reciprocating, pivoted rigid member, a reciprocating actuator, front and back limit stops for said member and means whereby said actuator, under closed circuit conditions, takes a position out of engagement with said bar. 110

In witness whereof I have signed my name to this specification.

JOHN J. GHEGAN.
